UNITED STATES PATENT OFFICE.

HERMIONE M. WILENSKY, OF ATLANTA, GEORGIA.

DESIGN FOR A PACK OF CARDS.

Application filed September 2, 1927. Serial No. 23,281. Term of patent 3½ years.

To all whom it may concern:

Be it known that I, HERMIONE M. WILENSKY, a citizen of the United States, residing at Atlanta, in the county of Fulton and State of Georgia, have invented a new, original, and ornamental Design for a Pack of Cards, of which the following is a specification, reference being had to the accompanying drawing, forming part thereof.

Fig. 1 is a plan view of the back of a card, showing my new design. Fig. 2 is a face view.

I claim:

The ornamental design for a pack of cards, as shown.

HERMIONE M. WILENSKY.
